JOSEPH HARRY GRUVER, OF BALTIMORE, MARYLAND, ASSIGNOR OF ONE-HALF TO
FRANCIS NORRIS, JR., OF RASPEBURG, MARYLAND.

NON-REFILLABLE BOTTLE.

1,104,420.

Specification of Letters Patent. Patented July 21, 1914.

Application filed August 9, 1913. Serial No. 784,003.

To all whom it may concern:

Be it known that I, JOSEPH HARRY GRUVER, a citizen of the United States, residing at Baltimore, Maryland, have invented certain new and useful Improvements in Non-Refillable Bottles, of which the following is a specification.

My present invention relates to the general type of non-refillable bottles and stoppers therefor disclosed in Letters Patent of the United States granted to me October 29th, 1912, No. 1042669, my object being to simplify the construction and to eliminate the inner sliding valve member and to make the stopper durable and efficient.

My object also is to provide a stopper which may be readily inserted within a bottle neck, the said bottle neck being especially formed with a groove and seat, the upper edge of the stopper being spun or pressed into the groove, and the seat determining the position of the stopper within the bottle neck.

In the accompanying drawings Figure 1 represents a sectional view of a bottle with my improved stopper in place therein. Fig. 2 is a side elevation of the stopper. Fig. 3 is a side view of the inner shell. Fig. 4 is a side view of the inner pronged member or guide for the ball. Fig. 5 is a plan view of said inner pronged member. Fig. 6 is a view of the stopper in section in the form in which it is manufactured previous to its application to the bottle, and Fig. 7 is a detail.

In these drawings the main shell of the stopper is indicated at 1, this being formed of thin sheet metal drawn into general cup form with an upper portion 2 of larger diameter than the lower main body portion, this forming an exterior shoulder at 3 and an upstanding rim being left at 4. Within the main shell an inner member 5 is arranged, this also being formed of sheet metal and having a cover portion 6 overhanging the shell 5 and projecting beyond the edge of the same, this cover portion 6 being connected with the inner shell 5 by the portions 7, thus leaving openings at 8 beneath the cover portion to allow the fluid to flow from the interior shell through these openings 8 and around the edge of the cover portion through the space 9 to be discharged from the bottle. Within the inner shell 5 a pronged member 10 is arranged and this may be variously formed, that is either from

sheet metal or otherwise. It is provided with a ring portion 11 at its lower end which is seated upon a packing ring 12, preferably of cork or soft material, which packing ring in turn is seated upon the bottom 13 of the outer shell, an opening being left at 14 in the bottom and through the ring packing. Enough of the inner edge of the ring packing is left exposed to furnish a seat for the ball valve 15. The pronged member has arms extending up from the base ring 11 and these arms have inwardly extending lugs 11^a which, when the bottle is in position for discharging its contents, will limit the movement of the ball 15 and prevent it from unduly obstructing the discharge openings 8. The inner and outer shells 1 and 5 of sheet metal are held together by simply indenting the said shells as indicated at 16. In placing the stopper within the bottle it is inserted until the shoulder 3 rests upon a packing 17 on the shoulder 18 of the bottle. This will locate the upstanding rim 4 in proper position to be turned or pressed outwardly into the groove 19 in the bottle neck. The instrument for spinning this rim 4 outwardly into the groove 19 may also press, at the same time that it does the bending or spinning of the flange 4, upon the inner shoulder of the outer member to thus press the stopper firmly upon the packing 17, and while so pressed the stopper will be locked in place by the flange 4 entering the groove 19. The packing 17 prevents the passage of gas or fluid around the outside of the stopper.

With my present construction it will be noticed that the inner member or shell 5 has no sliding movement, the only movable part being the ball valve 15, and by reason of this the stopper is adapted for use with liquids of different consistencies and of more or less sticky nature. Furthermore, by dispensing with the inner sliding member the stopper will not be put out of service should it become slightly bent or damaged in shipment or handling. The outer shell 1 is made of one piece, including its upper enlargement and its bottom portion 13. The inner pronged member fits freely within the shell 5 and serves to hold the cork seat in place and prevents said seat from bulging or becoming distorted under the action of the fluids. Only enough of this cork seat is left exposed to secure a

reliable contact with the ball. The cork will accommodate itself to any irregularities in the surface of the ball valve. The cork seat 12 is held under slight compression by the 5 inner pronged member. The ball valve is made of metal.

The form of bottle herein shown is like that disclosed in English Patent 24446 of October 25, 1912, and French Patent 449903 10 of October 26, 1912 granted to myself and F. Norris, Jr., and is also similar to the bottle disclosed in my application for Letters Patent of the United States No. 698,555.

With a bottle constructed with the inner 15 shoulder and groove above it and a stopper having an exterior shoulder and the locking rim above it, the stopper may be locked in place under pressure, that is, while it is pressed firmly upon its seat and when this 20 seat has the packing 17, the stopper can be locked in place with the packing under compression.

I prefer to form the inner pronged member with a flange 20 at its lower edge to 25 abut against the lower edge of the inner member or shell 5. The purpose of this is to keep the pronged member from working upwardly within the inner shell 5 and to keep the cork disk or washer from bulging up at its inner portion where the ball 30 valve is seated. Furthermore this flange will enable the pronged member to be quickly and easily assembled with the inner shell 5, no special or accurate fitting of these 35 parts being necessary but the pronged member being slipped freely into the shell 5, the flange acting to arrest it in proper position and to hold it there when the parts are assembled, as shown in Figs. 1 and 6.

40 I arrange in the mouth of the bottle a stopper 21, preferably of wood, which may be readily inserted or removed by hand. When this stopper, which fits the bottle mouth closely, is inserted it compresses the 45 air between it and the ball valve and serves to hold the ball valve to its seat in all positions that the bottle may assume, for instance in shipment or should it be desirable to lay the bottle on its side. It is desired that 50 the ball valve will remain seated and thus prevent the liquid from getting above the ball and filling the spaces within and above the stopper where this liquid would remain and give the bottle an appearance of not 55 being filled to the proper height, and further it is undesirable that the liquid should collect within and above the stopper. With the cork 21, however, the compression of the air below it will hold the ball valve to its 60 seat and the bottle may be inverted or placed on its side without liability of the liquid displacing it or getting above the ball.

I claim as my invention:

1. In combination in a non-refillable bottle, a bottle having a shoulder in its neck

facing upwardly with a groove close above said shoulder and a stopper consisting of a shell having an exterior shoulder to fit upon the shoulder in the bottle neck with yielding packing interposed, the said shell having an upwardly extending rim above said shoulder, the extreme upper edge of which is bent outwardly into the groove in the bottle neck, the main body of said shell extending below the said shoulder, and a valve carried by the 75 shell, substantially as described.

2. A non-refillable bottle stopper comprising a sheet metal shell having an upper enlargement providing an exterior and an interior shoulder and an upstanding rim and having a perforated bottom, an inner shell of sheet metal secured in fixed relation to the outer shell and having a cover portion located in the upper enlargement with lateral discharge openings below the same to deliver into said upper enlargement, an inner pronged member fixed in the inner shell, a cork seat between the pronged member and the bottom of the outer shell and a ball to rest on said cork seat, the said pronged member having stops to limit the movement of the ball, substantially as described.

3. A non-refillable bottle stopper comprising a sheet metal shell having an upper enlargement providing an upstanding rim 95 and an exterior and an interior shoulder and having an integral perforated bottom, an inner shell fixed to the outer shell and having a cover portion with lateral openings below the same to deliver into said upper enlargement, a ball valve, guide means on the inner side of the inner shell for the said ball valve and a cork washer, upon which the ball is seated, held between the bottom of the outer shell and the inner members, substantially as described.

4. In combination in a non-refillable bottle stopper, an outer shell having an enlarged upper portion providing an exterior shoulder and an upstanding rim, an inner member comprising a shell fixed to the outer shell and having a cover portion located within the upper enlargement and with lateral openings below it, and having interior guides, a washer forming a valve seat at the lower part of the exterior shell and held by said inner member and a ball valve fitted to said seat, substantially as described.

5. In combination in a non-refillable bottle stopper, an outer shell having an upper enlargement providing an exterior shoulder and an upstanding rim, an inner shell held in fixed relation to the outer shell and having a cover portion located above the plane of the inner bottom of said enlargement, with lateral openings beneath said cover and a ball valve closing an opening in the bottom of the outer shell.

6. In combination in a non-refillable bottle stopper, an outer shell adapted to be fixed in

the bottle neck and having an opening at its lower end, an inner shell carried immovably by the outer shell and having a cover portion with openings beneath the same for the discharge of the liquid, a ball valve, a washer at the lower end of the outer shell surrounding the opening and forming a seat for the said ball valve, an inner pronged member having a ring portion at its lower end resting upon the washer, said ring portion abutting against a portion of the inner shell which acts as a stop to prevent displacement of the pronged member, substantially as described.

7. In combination in a non-refillable bottle stopper, an outer shell adapted to be fixed in the bottle neck and having an opening at its lower end, an inner shell carried immovably by the outer shell and having a cover portion with openings beneath the

same for the discharge of the liquid, a ball valve, a washer at the lower end of the outer shell surrounding the opening and forming a seat for the said ball valve, an inner pronged member having a ring portion at its lower 25 end resting upon the washer, said ring portion abutting against a portion of the inner shell which acts as a stop to prevent displacement of the pronged member, the abutting of the pronged member against the inner shell being provided by a flange on the ring of the pronged member engaging the edge of the inner shell, substantially as described.

In testimony whereof, I affix my signature 35
in presence of two witnesses.
